UNITED STATES PATENT OFFICE.

JOHN McNAUGHTON, OF NEW YORK, N. Y.

DESIGN FOR A VEGETABLE SCRAPER AND PARER.

59,248.

Specification for Design.

Patented Oct. 4, 1921.

Application filed April 29, 1921. Serial No. 465,551. Term of patent 3½ years.

To all whom it may concern:

Be it known that I, JOHN McNAUGHTON, a subject of the King of England, residing at New York, in the county of New York and State of New York, have invented a new, original, and ornamental Design for Vegetable Scrapers and Parers, of which the following is a specification, reference being had to the accompanying drawing, forming part thereof.

Fig. 2 is a plan view thereof.

I claim:

The ornamental design for a vegetable scraper and parer, as shown.

JOHN McNAUGHTON.
